(57) **CLAIM**

The ornamental design for a tablet stand, as shown and described.

DESCRIPTION

FIG. 1 is a front perspective view of a tablet stand showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a rear, bottom perspective view thereof, showing the tablet stand in a folded position;

FIG. 10 is a front, bottom perspective view thereof;

FIG. 11 is a front perspective view thereof, showing the tablet stand in a fully opened position; and,

FIG. 12 is a rear perspective view thereof.

The broken line shown in the drawings represent portions of the tablet stand that form no part of the claimed design.
